(57) **CLAIM**

The ornamental design for a cord hook, as shown and described.

DESCRIPTION

FIG. 1 is an isometric view thereof;

FIG. 2 is a side view thereof, as taken from the left side of FIG. 1;

FIG. 3 is a side view thereof, as taken from the right side of FIG. 1 (the side views are mirror images of one another);

FIG. 4 is a rear view thereof;

FIG. 5 is a front view thereof;

FIG. 6 is a top view thereof; and,

FIG. 7 is a bottom view thereof.

The dashed lines in FIGS. 1–7 depict unclaimed portions of the design. The dashed lines and the structure they depict form no part of the claimed design. The dash-dot-dash lines in FIGS. 1, 2 and 3 define the boundary of the claimed design and form no part of the claimed design.
